UNITED STATES PATENT OFFICE.

ARTHUR HOLDSWORTH, OF OAK PARK, ILLINOIS.

WINDING BOARD.

Application filed April 3, 1922. Serial No. 548,967.

To all whom it may concern:

Be it known that I, ARTHUR HOLDSWORTH, a citizen of the United States, residing at Oak Park, in the county of Cook and State of Illinois, have invented a certain new and useful Improvement in Winding Boards, of which the following is a full, clear, concise, and exact description, reference being had to the accompanying drawings, forming a part of this specification.

My invention relates to the art of merchandising textile or other fabrics, and more particularly to the distribution of samples of such fabrics.

Such fabrics are usually wound on winding boards and piled on shelves back of the counter where they are to be sold.

In giving a sample from a bolt of goods, the salesman ordinarily cuts a small piece off the end of the fabric. This leaves the body of the cloth with an irregular end. In subsequently selling a piece from this bolt, it is not permissible to count the irregular projection extending across a portion of the width of the end of the fabric in the length sold. The cloth in this portion is either given to the customer without charge, or, if the salesman takes the trouble to do so, it may be cut off and saved for use in giving additional samples. If this piece is tucked between the cloth and the winding board, it soon becomes so wrinkled that it is better to throw it away than give samples from it; and unless it is kept with the bolt from which it has been cut, it might as well have been thrown away in the first place.

The practice of giving samples, involves a great waste of material in addition to that in the samples actually distributed, and, in the case of the more expensive fabrics, the money loss is very large.

To obviate this loss is the primary object of my invention.

In the accompanying drawings;

Figure 1 is an end view of a winding board, illustrating the application of the principles of my invention thereto; and

Fig. 2 is a perspective view partly broken away to show the interior mechanism.

The winding board to which my invention is applied may be of any suitable or preferred construction, and, in the embodiment selected for illustration, comprises spaced side pieces 10, braced by cross pieces, one of which is shown at 12, to form a strong

light frame. A covering 14, usually of paper, is suitably fastened on this frame and the board is complete.

According to my invention, one end cross piece 12, is provided with a slot 16, thru which a strip of fabric may be readily inserted by folding the same and tucking it thru the slot with any suitable tool, for instance, the pair of scissors carried by every salesman.

Suitable means are provided for resiliently holding the strip of fabric 18 in place with its end projecting slightly out of slot 16. The means illustrated comprises a plate 20 pivoted on a long pintle 22, and resiliently held over the inner end of slot 16 by a suitable spring 24.

To provide a durable pivotal mounting for pintle 22, a plate 26 functioning as a fixed hinge plate is preferably provided. The free edge of plate 20 is preferably curved or rolled as at 28, and in the position shown, the fabric 18 is lightly gripped between the plate 20 and the inner face of end piece 12.

In using such a device the exposed end of strip 18 can readily be pulled out a few inches and cut off to serve as a sample, until the strip is exhausted. When this occurs, another narrow strip is cut from the end of the main piece of fabric all across the width of the same, and folded back and forth upon itself to form a neat packet preferably from 2 to 4 inches long, with one end projecting therefrom. Plate 20 can be easily tipped up out of the way by inserting a pencil through slot 16, to permit the packet to be shoved through the slot with the butt of the salesman's scissors.

When all the material cut for giving samples is preserved and used in this way, one or two strips across the width of the fabric will usually provide all the samples required in selling the entire bolt of cloth; but it will be obvious that the greater the number of samples required by the nature of the trade or the class of customers supplied, the more useful the device becomes.

Winding boards according to my invention can be manufactured at only a trifling greater cost by reason of the addition of the device for holding the samples, and they will give service out of all proportion to such cost. The superiority of such a board over the use of a special sample holder, is due first, to the fact that a complete separate

holder is a nuisance to keep in place, and when misplaced results in giving incorrect samples and endless confusion; and second, in the high cost of such a device, which, 5 while perhaps not greater than the value of having samples satisfactorily kept, is unquestionably much greater than the value of such services as separate holders are capable of rendering.

10 Without further elaboration, the foregoing will so fully explain the gist of my invention, that others may, by applying current knowledge, readily adapt the same for use under various conditions of service, 15 without eliminating certain features which may properly be said to constitute the essential items of novelty involved, which items are intended to be defined and secured to me by the following claims:

20 I claim:

1. A winding board having, in combination, side pieces and an end piece, said end piece having a slot, and resilient means normally obstructing the inner end of said slot.

2. In a winding board, an end piece having a slot providing access to the interior

of said board, and fabric retaining means permanently associated with said board.

3. In a winding board, an end piece having a slot providing access to the interior 30 of said board, and resilient fabric retaining means adjacent the inner end of said slot.

4. In a winding board, an end piece having a slot providing access to the interior 35 of said board, and a retaining element overlying the inner end of said slot, said retaining element being resiliently mounted and movable out of the way to permit insertion of a sample strip.

5. In a winding board, a frame and cover therefor, a slot in one end of said board opening into the hollow interior, and a clip 40 resiliently held in place over the inner end of said slot.

6. In a winding board, a frame and cover therefor, a slot in one end of said board opening into the hollow interior, and a clip pivoted adjacent the inner end of the slot 45 and resiliently held in place over the same.

In witness whereof, I hereunto subscribe my name this 1 day of April, 1922.

ARTHUR HOLDSWORTH.
